TABLE

Morton R. Cohen, 5490 S. South Shore Drive,
Chicago, Ill.

Filed Aug. 12, 1957, Ser. No. 47,310

Term of patent 14 years

(Cl. D33—14)

Fig. 1 is a perspective view of a table showing my new design;

Fig. 2 is an elevational view of the same on an enlarged scale;

Fig. 3 is a sectional view through the same on the line 3—3 of Fig. 2 and in the indicated direction; and

Fig. 4 is a sectional view through the same on the line 4—4 of Fig. 2 and in the indicated direction.

The dominant features of my design reside in those portions shown in full lines on the drawing.

The legs not shown are like the leg shown but are indicated in broken lines for illustrative purposes only.

I claim:

The ornamental design for a table, substantially as shown and described.
